UNITED STATES PATENT OFFICE.

CHARLES BURTON WINZER, OF TOOTING, LONDON, ENGLAND, ASSIGNOR TO ERNST PAUL LEHMANN, OF BRANDENBURG-ON-THE-HAEL, GERMANY.

SPINNING-TOP.

974,731.

Specification of Letters Patent.

Patented Nov. 1, 1910.

Application filed July 31, 1909. Serial No. 510,612.

To all whom it may concern:

Be it known that I, CHARLES BURTON WINZER, a subject of the King of Great Britain and Ireland, residing at West Gardens, 5 Tooting, in the county of London, England, have invented Improvements in Spinning-Tops, of which the following is a specification.

The object of this invention is to provide 10 means for causing spinning tops to have a jumping or dancing motion while spinning. I obtain this object by the addition of a spring, in the construction of tops, and illustrate in the accompanying drawings the 15 methods of carrying my invention into effect.

Referring in the first place to the drawing A is a top with the spinning point removed and in place thereof a spiral spring B is attached, preferably of taper form, as shown

in the drawings, the end coil B¹ being flat to 20 form a flat spinning surface, the top will spin on this surface and have a jumping or dancing combined with an erratic motion while doing so.

What I claim, and desire to secure by Letters Patent of the United States, is:—

A spinning top having a peg consisting of a spiral spring the end of which is flat for the purpose of giving a combined jumping and erratic motion to said top while spinning. 30

In testimony whereof I have signed my name to this specification in the presence of two subscribing witnesses.

CHARLES BURTON WINZER.

Witnesses:

GEORGE ROYLE,
H. D. JAMESON.
